UNITED STATES PATENT OFFICE.

ROSCOE C. PATTISON, OF ROCHESTER, NEW YORK.

APPARATUS FOR USE IN MAKING CORES OR THE LIKE.

1,350,564.

Specification of Letters Patent. Patented Aug. 24, 1920.

Application filed September 2, 1919. Serial No. 320,969.

To all whom it may concern:

Be it known that I, ROSCOE C. PATTISON, a citizen of the United States, residing at Rochester, in the county of Monroe and State of New York, have invented a new and useful Improvement in Apparatus for Use in Making Cores or the like, of which the following is a specification.

This invention relates to apparatus for use in forming molds and cores of the kind used in metal molding.

The objects of the invention are to provide an apparatus of this kind by means of which a core box or pattern can be rapidly and accurately drawn from a core or mold without requiring the accuracy and skill which is necessary in withdrawing the core boxes or patterns by hand; also to provide an apparatus of this kind which rapidly alines the core box or pattern in such a manner that the withdrawing of the parts of the box or of the pattern can be quickly effected; also to provide an apparatus of this kind which is simple in construction and inexpensive to manufacture; also to improve the construction of apparatus of this kind in other respects hereinafter specified.

In the accompanying drawings:

Figure 1 is a side elevation of an apparatus embodying the invention showing a core box in place thereon.

Fig. 2 is a similar view thereof showing the movable parts thereof in different positions.

Fig. 3 is a top plan view thereof.

Fig. 4 is a transverse sectional elevation thereof on line 4—4, Fig. 3.

Fig. 5 is a central sectional elevation of one of the magnets detached from the apparatus.

Briefly stated, the apparatus shown in the drawings and embodying the invention includes a base having a supporting part on which the work, such as a core box with a core, may be placed, and guide portions or tracks on which one or more core box gripping devices or electromagnets are slidably arranged. These gripping devices or electromagnets are provided with faces or parts adapted to grip or to be drawn by magnetism into engagement with corresponding parts, plates or disks on the core box in such a manner as to aline the core box on the apparatus. When the core box is properly alined, the parts thereof may be withdrawn from the core by moving the gripping de-

vices or electromagnets lengthwise of the guide portions or tracks of the apparatus.

The apparatus is hereinafter described more particularly as used in connection 60 with the forming of cores, but it will be understood that the apparatus is not limited to such use but may be used for making molds or for analogous purposes.

A represents the base or frame of the 65 apparatus which may be of any desired shape or proportions, that shown having an enlarged intermediate portion preferably provided with raised ribs *a* on which a plate or board supporting an inverted core box 70 and a core may rest. The base is also provided with longitudinal guide rails or tracks *a'*, those shown forming the edges of a central slot extending lengthwise of the base, and being arranged parallel to the 75 plane of the upper faces of the raised ribs *a*. The base is preferably provided with a plurality of connecting members *a*² which connect the two sides of the frame and with feet or legs *a*³ by means of which the apparatus may be supported on a bench or 80 table. A frame or base of any other suitable construction may be employed.

Gripping devices or magnets are slidably arranged on the guide tracks of the base in 85 any suitable manner. In the construction shown these gripping devices have body portions *B* provided with base portions *b* having slots or guide parts adapted to co-operate with the guide rails or tracks *a'* so 90 that the gripping devices are movable lengthwise of the base. Any suitable means may be provided for causing the gripping devices to engage the core boxes relatively to the base of the apparatus. In the construction shown for this purpose the gripping devices are in the form of electromagnets, each comprising a coil *C* which is enclosed in an annular slot or recess in the head *c* of the gripping device. The coil 100 surrounds a central post or core *c'* and is preferably held in the recess by means of a disk or plate *c*² of non-magnetic material which may be held in place in any suitable manner, for example by means of a nut *c*³ 105 which engages the outer threaded end of the post or core *c'*. The open end or face *c*⁴ of the head *c* is preferably arranged in a plane perpendicular to the guide rail or track. The gripping device may be provided with 110 any desired means for facilitating the handling of the same, for example with a

projection c^5 on the top of the gripping device and with a handle or the like c^6 arranged at one end of the gripping device. Current may be conducted to the electromagnets by any suitable means, conductors c^7 being shown in the construction illustrated, and means (not shown) are preferably provided which are operable at will for connecting the conductors with a source 10 of power to energize the magnets.

In order to enable the core boxes to cooperate with the apparatus described, each 15 of the two halves $D D'$ of a core box is provided with parts with which the gripping devices can coöperate to aline the core box and to draw the two halves of the core box away from the core. When the gripping devices are in the form of electromagnets as shown, the core boxes must be either 20 made of magnetic material or if made of wood or other non-magnetic material, they must be provided with plates or parts d secured to the core boxes and provided with flat faces which are arranged in planes perpendicular to the direction in which the parts of 25 the core boxes must be moved in order to clear the core. These faces are so arranged on the core box as to coöperate with the faces of the electromagnets. $d' d^2$ represent 30 devices for locking the two parts of the core box together when the sand is packed therein, d^3 represents a plate or board which is adapted to be placed over the open end of the core box after the box is packed with 35 sand, and which forms a base or support for the core after the two halves of the inverted core box have been drawn from the core and E , Fig. 2, represents a core.

In the operation of the apparatus the core 40 box, after the sand has been thoroughly packed therein, is inverted and the plate d^3 is placed upon the supporting ribs a of the base. The gripping devices are then moved into operative relation to the core box and 45 the current is passed through the coils of the electromagnets to energize the same. When the electromagnets are energized, the outer faces of the plates or parts d will be drawn into contact with the faces c^4 of 50 the electromagnets, so that the core box will be properly alined on the base. The locking devices which hold the two parts of the core box together are then released and the two halves of the core box can be drawn 55 away from the core by moving the gripping devices lengthwise of the guide tracks. By means of this apparatus the making of cores is greatly facilitated so that this work can be done by unskilled men. It is not necessary 60 to use any precautions in drawing the parts of the core box away from the core since by means of the electromagnets the proper alining of the core box on the apparatus is insured and the guide rails insure 65 the proper drawing of the parts of the

core box away from the core so as to prevent any damage to the core.

I claim as my invention:

1. In an apparatus for forming sand, the combination with a sand-forming device, of 70 a base having a part adapted to receive the sand-forming device, and a gripping device adapted to engage said forming device to aline the same on said base and adapted to be moved relatively to said base to move 75 said forming device from the formed sand.

2. In an apparatus for forming sand, the combination with a sand-forming device, of 80 a base having a part adapted to receive the sand forming device, guide means on said base, and a gripping device movable on said guide means and adapted to engage said forming device to aline the same on said base and to move said forming device from the formed sand.

3. In an apparatus for forming sand, the combination with a sand-forming device, of 85 a base having a part adapted to receive the sand-forming device, guide means on said base, and a gripping device movable on said 90 guide in a plane substantially parallel with the plane of the sand-receiving part of said base, said gripping device being adapted to remove said forming device from the formed sand.

4. In an apparatus for forming sand, the combination with a sand-forming device, of 95 a base having a part adapted to receive the sand-forming device, guide means on said base extending into proximity to said receiving part, a pair of gripping devices adapted to engage different parts of said sand-forming device and to move said parts in opposite directions from the formed sand.

5. In an apparatus for forming sand, the 105 combination with a sand-forming device, of a base having a part adapted to receive the sand-forming device, guide means on said base extending into proximity to said receiving part and arranged in a plane substantially parallel to the plane of said receiving part, and a pair of gripping devices 110 movable along said guide means and adapted to engage different parts of said forming device to aline said device with said guide 115 means, said gripping devices being adapted to move said sand-forming device from the formed sand.

6. In an apparatus for forming sand, the 120 combination with a sand-forming device, of a base having a part adapted to receive the sand-forming device, guide means on said base arranged in a plane parallel to the plane of said receiving part, a magnet movable on said guide means, and a part of 125 magnetic material on said forming device with which said magnet may coöperate to draw said sand-forming device from the formed sand.

7. In an apparatus for forming sand, the 130

- combination with a sand-forming device, of a base having a part adapted to receive the sand-forming device, guide means on said base arranged in a plane parallel to the plane 5 of said receiving part, a magnet movable on said guide means and having a flat face, and a flat face of magnetic material on said sand-forming device with which said face of the magnet is adapted to coöperate for alining 10 said sand-forming device with said guide means, said magnet being movable on said guide means to draw said sand-forming device from the formed sand.
8. In an apparatus for forming sand, the 15 combination with a sand-forming device, of a base having a part adapted to receive the sand-forming device, guide means on said base arranged in a plane parallel to the plane of said receiving part, a pair of electromagnets movable on said guide means, and parts 20 of magnetic material on said sand-forming device adapted to be engaged by said electromagnets for drawing said sand-forming device from the formed sand.
- 25 9. In an apparatus for forming cores, the combination with a core box having a part of magnetic material secured thereto, said part having a face arranged in a plane extending substantially at right angles to the line along which said core box must be removed from the core, of a base for said apparatus, means on said base, and a magnetic device movable on said guide means and having a face extending substantially at 30 right angles to said guide means, said magnetic device being adapted to draw the face of said part into contact with the face of said magnetic device for alining said core box on said base, said magnetic device being movable in said guide means to withdraw said core box from the core.
- 35 10. In an apparatus for forming cores, the combination with a core box made in two parts, each of said parts having a portion of magnetic material provided with a face arranged substantially in a plane at right angles to the line along which the part of the core box must be removed from the core, of a base for said apparatus having guide 40 means, a pair of magnets movable in said guide means and having flat faces arranged in a plane extending substantially at right angles to the direction of movement of said magnets, said magnets being adapted to 45 draw said flat faces of said portions of the core box into contact with the flat faces of said magnets to aline the core box on said base and being movable to withdraw said parts of said core box from the core.
- 50 55 60 11. In an apparatus for forming cores, the combination with a core box having a part of magnetic material secured thereto, said part having a face arranged in a plane extending substantially at right angles to the line along which said core box must be removed from the core, and a plate on which said core box and core are adapted to rest, of a base for said apparatus having means for supporting said plate, guide means on said base extending into operative relation 65 to said plate supporting means, and an electromagnet movable on said guide means and having a face extending substantially at right angles to the direction of movement of said electromagnets, said electromagnet 70 when energized drawing the face of said part of the core box into substantially parallel relation to the face of said electromagnet for alining said core box on said base and drawing said core box from the core when 75 said magnet is moved on said guide means.
12. In an apparatus for forming sand, the combination with a sand forming device having a part of magnetic material, guide means extending into operative relation to 80 said device, and a magnet movable on said guide means into engagement with the magnetic material of said device to aline said device with regard to said guide means and to draw said sand forming device from the 85 formed sand.
13. In an apparatus for forming sand, the combination with a sand forming device having a part of magnetic material, a base having a part adapted to receive said sand 90 forming device and a guide portion, an electro-magnet movable on said guide means into operative relation to said magnetic material on said device, to aline said device with regard to said guide means and to draw 95 said sand forming device from the sand.
14. In an apparatus for forming sand, the combination with a sand forming device, of guide means extending into operative relation to said sand forming device, a gripping device movable on said guide means, and co-operating parts on said gripping device and on said forming device whereby said gripping device is adapted to first aline said sand forming device with regard to said guide device and then withdraw said sand forming device from the formed sand by the movement of said gripping device on said guide 100 means.
